DESIGN.

—o—
G. H. BALCH.
SPOON, FORK, &c.

No. 19,285.

Patented Aug. 27, 1889.

UNITED STATES PATENT OFFICE.

GEORGE H. BALCH, OF NEWBURYPORT, MASSACHUSETTS, ASSIGNOR TO THE
TOWLE MANUFACTURING COMPANY, OF SAME PLACE.

DESIGN FOR A SPOON, FORK, &c.

SPECIFICATION forming part of Design No. 19,285, dated August 27, 1889.

Application filed July 15, 1889. Serial No. 317,645. Term of patent 7 years.

To all whom it may concern:

Be it known that I, GEORGE H. BALCH, of Newburyport, in the county of Essex and State of Massachusetts, have invented and produced 5 a new and original Design for Spoons, Forks, and other Articles of Flatware, of which the following is a full, clear, and exact description, reference being had to the accompanying photograph, which forms part of this specification, 10 and which represents my new design as applied to a spoon.

The feature of my design consists in the ornamentation of the face or front portion of the handle of the article, the same, as shown in 5 the accompanying photograph, comprising the representation of a crossing curved band-like figure *b*, ornamented by flutes *c*, and above this figure an inverted horn and scroll-like

figure *d*. Below this curved band-like figure *b* are a series of reverse scroll-like ornaments 20 *e*, having pendent clavate-like figures *f*, the whole presenting the general appearance of a serpentine figure, and below this are a series of curved leaf-like figures *g*, which appear to gradually diminish toward the inner end of 25 the handle.

I claim—

The within-described design for spoons, forks, and other articles of flatware, substantially as represented in the accompanying 30 photograph.

GEORGE H. BALCH.

Witnesses:

ASA W. EMERSON,
EDWARD H. BARTLETT.
